UNITED STATES PATENT OFFICE.

THOMAS W. TITUS, OF SOUTH HAVEN, KANSAS.

ANTIRATTLER.

Application filed September 8, 1922. Serial No. 586,967.

To all whom it may concern:

Be it known that I, THOMAS W. TITUS, a citizen of the United States, residing at South Haven, in the county of Sumner and State of Kansas, have invented certain new and useful Improvements in an Antirattler, of which the following is a specification.

My invention relates to improvements in anti-rattlers, and has particular reference to anti-rattlers used on steering columns of Ford automobiles.

An object of my invention is to provide an anti-rattler that may be easily mounted on any Ford automobile now in use, and is adapted to prevent the rattling of the spark and gas control levers against the steering column.

A further object of my invention is to provide an anti-rattler that is adapted to be placed anywhere on the steering column under the hood of a Ford, that will positively prevent lateral movement of the spark and gas control rods thereby obviating the rattle.

A still further object of my invention is to provide an anti-rattler, that is strong, durable, very simple and inexpensive in construction, and that is well adapted to the purpose for which it is designed.

Other objects and advantages of the invention will become apparent during the course of the following description.

In the accompanying drawings, forming a part of the description, and wherein like numerals are employed to designate like parts throughout the same,

Figure 1 is an elevation showing my invention in use,

Figure 2 is a perspective view of the same, and

Figure 3 is a section taken on line 3—3 of Fig. 2 looking in the direction of the arrow.

In the accompanying drawings, wherein for the purpose of illustration is shown a preferred embodiment of my invention, the numeral 5 designates an ordinary steering wheel which is connected to the steering column 6. The numeral 7 designates the ordinary dash board 7 on which is mounted the plate 8, through which the steering column 6 runs. The numeral 9 designates the portion of the steering column 6 below

the dash 7 and the gas and spark levers are indicated by the numerals 10 and 11 respectively. 55

My invention comprises a metallic strip, which is designated in its entirety by the numeral 12, said strip being bent intermediate its ends so as to form a curved portion 60 13, which is provided on its inner face with a felting or the like 14 to allow the cross rod 10 to rotate therein, but does not allow lateral movement thereof. The member 12 is further bent to form the portion 15 which 65 is adapted to encircle the steering column 9, and terminates in a reduced portion 16 similar to the portion 13, which is adapted to engage the gas rod 11. The member 16 is also provided with a felt like material on 70 the inner surface and is designated by the numeral 17. A bolt 18 is adapted to pass through the opposite sides of the member 12 between the steering column and the gas rod 11, and the bolt 18 is provided on its 75 lower end with a nut 19. It will thus be seen, that by tightening the nut 19 the member 12 will be caused to grip the steering column, the gas and spark rods, and thereby prevent lateral movement of the spark rods. 80

In use, the ends 16 are spread apart so as to allow the same to pass over the steering column 9 until the portion 13 fits snugly against the gas rod 10 and the portion 16 fits snugly around the spark rod 11. It 85 will thus be seen that when the nut 19 is tightened on the bolt 18 the member 12 will be caused to firmly grip the gas and spark rods as well as the steering column 9. It is to be noted, that due to the felt members 90 14 and 17 the spark and gas rods will be free to rotate therein, but will not be free for lateral movement thereof.

It is to be understood that the form of my invention herewith shown and described is 95 to be taken as the preferred embodiment of the same, and that various changes in the shape, size and arrangement of parts, may be resorted to without departing from the spirit of my invention or the scope of the 100 appended claims.

Having thus described my invention, what I claim is:—

1. In combination with a steering column including spark and gas rods, an anti-rattler provided with felt portions to allow said 105

spark and gas rods to rotate, but to guard against lateral movement thereof.

2. In combination with a steering column including spark and gas rods, an anti-rattler adapted to be clamped around said steering column, spark and gas rods, felt portions secured on the inner surface of said anti-rattler, and means to clamp said anti-rattler on said steering column, spark and

gas rods to prevent lateral movement of 10 said spark and gas rods.

In testimony whereof I affix my signature in presence of two witnesses.

THOMAS W. TITUS.
